UNITED STATES PATENT OFFICE.

MARQUIS C. FORD, OF DENVER, COLORADO.

FEED-REGULATOR FOR CONCRETE-MIXERS.

1,253,022.

Specification of Letters Patent.

Patented Jan. 8, 1918.

Application filed December 20, 1916. Serial No. 138,006.

To all whom it may concern:

Be it known that I, MARQUIS C. FORD, a citizen of the United States, residing at Denver, in the county of Denver and State of Colorado, have invented new and useful Improvements in Feed-Regulators for Concrete-Mixers, of which the following is a specification.

My present invention pertains to feed regulators for concrete mixers and it has for its object to provide a simple, inexpensive and easily operated organized mechanism for properly mixing cement with gravel, broken stone or the like, and one which requires but little attention on the part of the operator and which in proportion to its size is possessed of large capacity.

The invention in all of its details will be fully understood from the following description and claims when the same are read in connection with the drawings, accompanying and forming part of this specification, in which:

Figure 1 is a side elevation of the machine embodying the feed regulating mechanism constituting the best practical embodiment of my invention that I have as yet devised.

Figs. 2 and 3 are elevations of the ends of the machine.

Fig. 4 is a longitudinal, vertical section of the machine.

Fig. 5 is a top plan view of the same.

Fig. 6 is a detail section, taken through the rotary elements for supplying the proper proportions of gravel and cement to the rotatable mixing cylinder.

Fig. 7 is a section taken through the rotary cement deliverer in the plane indicated by the line 7—7 of Fig. 6.

Fig. 8 is a detail longitudinal-vertical section taken in a plane at one side of the rotary gravel deliverer and showing the adjusting and adjustably fixing means complementary thereto.

Similar numerals of reference designate corresponding parts in all of the views of the drawings.

The main frame 1 of the machine embodying my novel mechanism may be of any construction compatible with the purpose of the machine, and on said frame is fixed a hopper 2 in which gravel is placed manually or otherwise in the discretion of the party using the invention. Also fixed on the frame is a hopper 3 in which cement is

placed by hand or in any other approved manner. It will also be noted that the main frame serves for the support of a water tank 5 which is for the sake of compactness disposed under the gravel hopper 2.

As best shown in Fig. 3, the gravel hopper is provided at one side of its discharge orifice with a fixed transversely-inclined wall 6, and opposed to the outer or free edge of said wall 6 is a door 7 for regulating or controlling the flow of gravel through the said discharge orifice. The said door 7 is hinged at its rear end to the hopper 2, and connected to and extending laterally from the door is a toothed bar 8 which is disposed and adjustable in an aperture 9 in one side wall of the hopper, Fig. 4, and is designed to adjustably fix the door 7 with respect to the wall 6, for the purpose hereinbefore set forth. It will also be noted by reference to Fig. 4 that the forward or discharge portion of the hopper 2, which portion is numbered 5^a, is equipped with a pendent hinged door 10 which is designed to guide the gravel into the buckets of the rotary gravel deliverer 11, said buckets being numbered 13, and is adapted by giving forwardly to the pressure of the gravel to assure the supply of an even stream of gravel to the buckets and in that way conducive to the successful operation of the machine. It will also be noted in this connection that incidental to the rotation of the deliverer 11 in the direction indicated by arrow in Fig. 4, under the pressure of the gravel, the door 10 will be opened by the wall of each bucket 13, and will be permitted, after the passing of the same, to gravitate to an approximately closed position.

The rotary gravel deliverer is loosely mounted on a transverse shaft 12, journaled in the main frame, and fixed to said shaft is a hand lever 16, designed to coöperate with the segmental rack 17 that is fixed to the side of the deliverer 11, as best shown in Fig. 8.

At the opposite side of the gravel deliverer 11, with reference to the lever 16 and the rack 17, is located the rotary cement deliverer 14 of the machine, said deliverer 14 being best shown in Figs. 1, 6 and 7. By reference to the said figures it will be noted that the deliverer 14 is made up of a cylinder 40, fixed to the deliverer 11 and having longitudinal apertures 41 in its circular wall, radial walls 42 fixed to the said cir-

cular wall of the cylinder and extending inwardly therefrom, each at one side of one opening 41, end walls 43 fixed on the shaft 12 and loosely arranged in the circular wall 5 of the cylinder 40, see Fig. 6; and radially-disposed walls 44 fixed at their ends in the end walls 43 and having curvilinear lips 45 disposed in parallel relation to the wall of the cylinder 40. By adjusting the lever 16, 10 the walls 44 may be moved toward or from the walls 42 to diminish or increase the capacity of the buckets in the cement deliverer 14, and by placing said lever 16 in engagement with the rack 17, the said walls 15 44 may be adjustably fixed in the positions in which they are placed. In this way the portions of cement fed by the deliverer 14 when rotated by the gravitation of cement from the hopper 3 may be nicely regulated. 20 Under the deliverers 11 and 14 is a receptacle 18 to which the gravel and cement are delivered and in which they are first commingled, and from said receptacle 18 the commingled substances pass through a chute 25 19 to the receiving end of a rotary mixing cylinder 20, which cylinder is preferably tapered toward its receiving end and may if desired be belled so as to prevent the mixture passing too freely from its comparatively large discharge end. The said cylinder 20 is provided with peripheral flanges 21, disposed in circumferentially grooved supporting wheels 22, and is also provided 30 with an exterior spur gear 28, with which is intermeshed a spur gear 29, Fig. 1, on a shaft 30, equipped with a pulley 31 that is designed to be connected through a band 32 with a motor (not shown). Interiorly the cylinder 20 is provided with mixing 35 blades 23 which are disposed longitudinally and are fixed to the cylinder wall. 40

A pipe 24 leads from the water tank 5 to about the point shown in the length of the cylinder 20, and said pipe is provided with 45 a valve 25 to enable the operator of the machine to conveniently control the supply of water. With the water supply pipe 24 arranged as shown relatively to the cylinder 20, it will be manifest that in a portion of 50 the cylinder the gravel and cement will be mixed in a dry state, while in the remainder of the cylinder the mixture will be effected with the material in a wet state.

From the comparatively large end of the 55 cylinder 20, the mixture passes to a pan 26, which is closed at one end and is provided with trunnions 27, journaled in a sub-frame 50 whereby when the pan is full, it may be conveniently rocked to discharge its contents 60 through its open end.

The practical operation of my novel machine will be fully understood from the foregoing, and it is therefore deemed unnecessary to again recite the operation of 65 the machine in detail.

It will be gathered from the foregoing that my novel organized mechanism is calculated to produce a mixture having uniform proportions of cement and gravel; and it will also be gathered that the machine is 70 simple and compact in construction, requires but little power for its proper operation and embodies no delicate parts such as are likely to get out of order after a short period of use. 75

It is to be understood that the machine herein shown and described is the best practical embodiment of my invention of which I am at present cognizant, but in the future practice of the invention, it is obvious that 80 certain changes may be made in the construction, proportions and relative arrangement of parts without involving departure from the scope of my invention as defined in the claims appended. 85

Having described my invention, what I claim and desire to secure by Letters Patent, is:

1. In feed regulating means, the combination of an inclined hopper for gravel or broken stone having a discharge orifice at its lower end and also having a pendent, normally-vertical swinging door for controlling the passage of gravel or comminuted stone through said orifice; said door extending below said hopper and orifice, and a rotary deliverer arranged below said hopper and orifice and receiving said pendent door and having buckets to receive gravel or comminuted stone from the hopper and deliver 100 the same successively; the said buckets being arranged to intersect the plane of the pendent door and to open and pass the latter. 95

2. The combination in feed regulating 105 means, of a suitably supported shaft, rotatable about its axis, a rotary deliverer loosely mounted on said shaft, means connected with the shaft and deliverer and constructed and arranged to adjustably fix each with respect to the other, and a rotary deliverer arranged alongside the first-named deliverer and comprising a cylinder fixed to the latter and having openings in its circular wall and also having radial walls fixed to 110 said circular wall, end walls fixed on the shaft and arranged in said circular wall, and radial walls fixed to said end walls and opposed to the radial walls on the circular wall. 115

3. The combination in feed regulating 120 means, of a suitably supported shaft, rotatable about its axis, a rotary deliverer loosely mounted on said shaft, means connected with the shaft and deliverer and constructed and arranged to adjustably fix each with respect to the other, and a rotary deliverer arranged alongside the first-named deliverer and comprising a cylinder fixed to the latter and having openings in its circu- 125 130

lar wall and also having radial walls fixed to said circular wall, end walls fixed on the shaft and arranged in said circular wall, and radial walls fixed to said end walls and 5 opposed to the radial walls on the circular wall, and having curvilinear lips disposed in parallel relation and adjacent to the circular wall of the cylinder.

4. The combination in feed regulating 10 means, of a rotary deliverer, a second rotary deliverer arranged alongside the first-named deliverer and comprising a cylindrical portion having openings in its circular wall, means in the cylindrical portion and in communication with said openings forming

buckets, said buckets being adjustable as to size, and means connected with said means in the cylindrical portion and extending loosely through and connected with the first-named deliverer and constructed and arranged to adjustably fix the size of the buckets in the second-named deliverer. 20

In testimony whereof I have hereunto set my hand in presence of two subscribing witnesses.

MARQUIS C. FORD.
